SHIRT

Ely Lesavoy, Allentown, Pa., assignor to Purling Mills,
Inc., Reading, Pa., a corporation of Pennsylvania

Filed Dec. 13, 1962, Ser. No. 72,834

Term of patent 14 years

(Cl. D3—25)

FIG. 1.

FIG. 2.

4 FIG. 3.

FIG. 4.

FIG. 1 is a front view of a shirt, showing my new design;

FIG. 2 is an enlarged fragmentary view of the sleeve portion shown in full lines at the right side of FIG. 1, as seen from the rear;

FIG. 3 is a front view thereof; and

FIG. 4 is an end elevational view of FIG. 3 as seen by looking in the direction of the arrows 4-4 on FIG. 3.

The portions of the shirt not shown are conventional.

The characteristic features of my new design reside in the quarter cuff in combination with the diagonal placket that overlies the plain uncuffed sleeve end portion, all as shown in full lines.

I claim:
The ornamental design for a shirt, substantially as shown and described.
